AIRCRAFT ADVERTISING

John C. Haddeck, Wilkes-Barre, Pa., and Zantford D. Granville, Springfield, Mass.; Alta M. Granville administratrix of said Zantford D. Granville, deceased

Application April 13, 1932, Serial No. 605,070

4 Claims. (Cl. 40—127.1)

Although this invention relates particularly to means for advertising in the air, it is not the purpose of the applicants to limit it to such.

It has been found impractical to use the exhaust gases alone to produce a dense or sufficiently permanent smoke cloud, or to use a separate apparatus to form and emit the clouds of smoke, so we have provided an apparatus and method for creating this smoke effect that is superior to any known.

One of the objects of our invention is to provide an apparatus that can be conveniently installed in any airplane and to render the same easily accessible to the control of the driver.

Another object of our invention is to provide an apparatus having a needle control valve approximately at the injection jet itself. The advantage of having the control located at this point eliminates lag in the emitting of smoke instantly, when pressed, inasmuch as the oil has a very short distance to travel before it vaporizes.

In addition, the shutting off of the fuel in this fashion, prevents the dripping of oil into the exhaust pipe. In the absence of this type of shut-off, the smoke apparatus will cause a ragged stream of smoke to trail the main column after the control has been shut off. This smudge of trailing smoke is prevalent on all other types of injection systems and of course is fatal to good skywriting. The shut-off must be clean, so with this apparatus it is possible to write dots and dashes which are absolutely perfect and which have no connecting strings of smoke which would tend to mar the clearness of each mark.

Another object of our invention is to have, at all times, a constant pressure at the nozzle. This constant pressure is created by means of an oil pump which will rapidly draw the liquid from the tank and thoroughly mix the oil with any appropriate chemical and will keep the two thoroughly mixed at all times. This eliminates the necessity of mixing the materials before placing them in the tank.

Another object of our invention is to provide a needle control valve and jet assembly which is capable of convenient removal, cleaning and replacing of a jet in a short space of time. In most types of assembly the lack of convenient accessibility has proven very detrimental.

The invention will be best understood from further description with reference to the attached drawing illustrating a practical embodiment of the same.

Referring to the drawing:

Figure 1 represents an airplane with the apparatus attached thereto.

Figure 2 is a section and elevation of the various parts of the apparatus.

Figure 3 is a detailed sectional view of the nozzle attachment.

Figure 4 is an elevation of the smoke control lever.

In the illustrative embodiment, the plane 10 is shown in Figure 1 with the apparatus attached thereto. Referring to Figure 2, the fuel injection system, comprises a tank 11, which contains a supply of smoke producing substance, said tank having an outlet 12, an inlet 12', a return pipe 13, and a vent 13'.

Located between the supply tank 11 and the pressure regulating valve 14, is an oil pump 15, preferably driven by the plane engine, which pumps the mixture from tank 11 through the pipes 12 and 16 into the needle control valve 18, then through the needle 19 to the nozzle 20 where it is vaporized by the heat of the gases in the exhaust pipe 21.

The pressure regulating apparatus comprises a valve 14, having a passage 14' connecting directly with pipes 16 and 17, and a second passage 23 extending vertically therefrom. A suitable pressure gage 25 is conveniently connected with the valve body as at 24, said gage located on the dashboard at 26. The passage 23 and the pipe 13 provide means for returning the liquid to the supply tank.

Connecting with the upper end of the passage 23 and forming a valve seat 28 at their juncture, is a compartment 27 containing a ball valve 29 normally held down by a spring 30, which is controlled by the threaded pressure adjusting screw 31.

The injection control apparatus comprises a valve 18 having a connection 32 for the pipe 17. The inlet passage 33 opens into the main passage 34 which is provided with a seat 35 for the needle control 19. Leading downwardly from the main passage 34 is an outlet 36 which is connected to the nozzle 20 as at 37.

Secured to the exhaust pipe 21 is a supporting member 22 for the nozzle 20. The nozzle consists of a lower section 38 perforated at 39 to allow the mixture to flow into the exhaust pipe 21, where it is vaporized by the heat of the exhaust gases.

The nozzle 20 has an enlarged portion 40 which is flanged at 41. The nozzle 20 is secured to a threaded member 42 by a nut 43. The threaded member 42 is connected to the lower portion of the injection control valve and permits the passage of the liquid thru the smaller passage 36 in valve 18, to the passage 44 in the member 42, to the passage 45 in the nozzle 20, and then thru the jets to be vaporized.

Ordinarily, the needle control 19 is seated by the spring 46 but is released by manipulation by the operator of the lever 47, (see Fig. 4) which is located on the control stick 48 of the plane. The lever is attached to the stick 48 by means of the screws 49. Integrally attached to the lever 60

47 is a tube 50, adapted to receive the cable 51 and is secured at 52. The other end of the cable 51 is secured to the link 53, which is secured to the injection control apparatus by means of a 5 nut 54.

Located below the fuselage and just back of the exhaust pipe 21 is a powerful searchlight 55, so positioned as to permit the dense clouds of smoke emitting from the exhaust pipe to flow 10 over and around and permitting the beam of light from the searchlight to be cast upon the dense clouds of smoke while flying thru the air, regardless of the speed of the plane.

The operation of the apparatus is as follows:

15 Prior to the operation of the device to produce the meteor or comet effect, while the plane is in flight, the pump 15 which operates with the engine of the plane, is continuously drawing the liquid from the tank 11 and directing it to the 20 valve 14. The needle control valve 18 being normally closed, prevents the flow of the liquid thru the pipe 17, the pressure thereby opening the ball valve 29 and permitting the liquid to return to the tank 11 thru the outlet 56 and the pipe 13.

25 The above described operation insures a complete mixture of the oil or other liquid and any suitable chemical for producing a smoke effect. If so desired, a chemical may be introduced for imparting a suitable color to the smoke stream.

30 Any sulphur dye of reddish tint which would not be decomposed by the heat of the exhaust pipe would give the smoke a very red glow, or if another color would be desired, such as green, the use of barium nitrate in finely divided form 35 may be mixed intimately with the oil, and when the charge is fired by the exhaust gases the vapor will have a brilliant green appearance. Similarly, other striking colors may be produced by the selection of suitable materials.

40 The operator of the plane, while flying, wishing to create a meteor or comet effect, manipulates the control stick lever 47 which releases the needle control 19 from its seat 35, which allows the liquid to flow thru the small opening 36, and then thru 45 the passages 44 and 45 into the nozzle 20, and then thru the jets 39 into the exhaust pipe 21 where it becomes vaporized, and then passes out of the exhaust opening in the form of a heavy smoke-like vapor to be eventually illuminated by the 50 rays from the searchlight 55.

The oil pump 15 permits of a high pressure at all times, and is controlled by a relief valve 14 and a pressure gage 25. The pressure may be adjusted by the pressure adjusting screw 31.

55 When the needle control 19 is seated, the flow of the liquid is stopped and as the oil pump 15 continues to force the liquid thru the pressure regulating valve 14, the liquid no longer escapes thru the injection valve 18, and a back pressure 60 results, thereby raising the ball 29 from its seat 28, and so returns thru the passage 56 to pipe 13 and into the liquid tank 11, and at the same time registers pressure on gage 25.

65 Calling your attention to the location of the needle control 19, the close proximity of the needle to the outlet nozzle prevents and eliminates any lag in the shutting off of the flow of the liquid. Because of the short distance the 70 liquid has to travel before vaporizing, it allows no ragged stream of smoke to train the main column after the flow has been cut off. With this clean shut-off, it is possible to write absolutely perfect

dots and dashes, with no connecting strings of smoke whatever.

This system makes an ideal installation for skywriting, laying a smoke screen, or when using it at night with a very powerful searchlight. In 5 placing the searchlight inside the stream of smoke it will give forth the appearance of a huge ball of fire shooting across the sky, resembling very closely a huge shooting star or meteor. The rays of light are reflected in the column of smoke 10 and give it a reddish glow, resembling a terrifically hot ball of fire at the light and gradually diminishing into what appears to be a sheet of flame several hundred feet to the rear of the ship.

15 As the invention may be applied with various modifications to the various forms of construction of planes without departing from its spirit and scope, the appended claims are not intended to limit the same to the specific form disclosed.

20 We claim:

1. In a smoke producing apparatus, a heated conduit, means for introducing a smoke producing substance under pressure, and means for maintaining a constant pressure, said means comprising a pressure control valve, said valve 25 having means for adjusting to a predetermined pressure, emission means comprising a needle control and a nozzle, said needle located in close proximity to the nozzle, and means for creating a meteor or comet effect, said means including a 30 searchlight directly in front of the heated conduit outlet so that the stream of smoke-like substance will pass around and over said searchlight.

2. In a smoke-producing apparatus, an exhaust pipe of a motor driven aircraft, means for emitting a stream of smoke-like substance and means for illuminating said stream for a substantial distance beginning at the point of emission of said stream, said means including a 35 searchlight positioned directly in front of the exhaust pipe outlet so that the stream of smoke-like substance will pass over and around said searchlight.

3. In an aeroplane, an exhaust pipe means for creating a meteor or comet effect in the air including a supply chamber, means connected to the power plant for pumping the smoke producing liquid from the supply chamber to the exhaust pipe, and means for regulating the pressure of said liquid, and registering said pressure, means 45 for controlling said liquid's entrance into a perforated nozzle and under the control of the operator of the aeroplane, said perforated nozzle extending into said exhaust pipe, a searchlight so located in the path of emission of the smoke 50 from the exhaust pipe when the aeroplane is in flight as to cause the illuminated smoke to take the appearance of a huge ball of fire.

4. In an aeroplane, an exhaust pipe means for creating a meteor or comet effect in the air including a smoke-producing apparatus connected to and operated by the power plant, said smoke-producing apparatus provided with a perforated emission nozzle extending into the exhaust pipe of the aeroplane, a searchlight positioned in respect to the outlet end of said exhaust pipe so that the smoke emitting therefrom will pass over and around said searchlight to permit the rays from the searchlight to be reflected upon the smoke and give the appearance of a huge ball of 70 fire.
